UNITED STATES PATENT OFFICE

115,507

DESIGN FOR A BUILDING

Nathaniel A. Owings, Chicago, Ill., assignor to
Stefco Steel Company, Michigan City, Ind., a
corporation of Illinois

Application April 28, 1939, Serial No. 84,654

Term of patent 14 years

To all whom it may concern:

Be it known that I, Nathaniel A. Owings, a citizen of the United States, residing at Chicago, in the county of Cook and State of Illinois, have invented a new, original, and ornamental Design for a Building, of which the following is a specification, reference being had to the accompanying drawings, forming part thereof:

Figure 1 is a front elevation of a building showing my new design.

Figure 2 is a side elevation looking at the right hand side of Figure 1.

Figure 3 is a side elevation looking at the left hand side of Figure 1.

Figure 4 is a top plan view.

Figure 5 is a rear elevation.

I claim:

The ornamental design for a building, as shown.

NATHANIEL A. OWINGS.
